COMBINED WASTE RECEPTACLE AND DISPENSER FOR DISPOSABLE LINERS Edward E. Heck, Berwyn, Ill., assignor to Republic Mold-
ing Corporation, Niles, Ill., a corporation of Illinois

Filed Aug. 30, 1968, Ser. No. 13,336

Term of patent 14 years

Int. Cl. D7—06

U.S. Cl. D49—35

FIG. 1

FIG. 2

FIG. 4

FIG. 5

FIG. 3

FIG. 6

FIG. 7

FIG. 8

FIG. 9

FIG. 10

FIG. 1 is a perspective view of a combined waste receptacle with the top cover opened and a liner dispenser (in exploded position) embodying my new ornamental design;

FIG. 2 is a front elevational view of the waste receptacle;

FIG. 3 is a rear elevational view of the waste receptacle;

FIG. 4 is an elevational view of the left hand side of the waste receptacle, the right hand side view being identical thereto;

FIG. 5 is a top plan view of the waste receptacle;

FIG. 6 is a bottom plan view of the waste receptacle;

FIG. 7 is a top plan view of the liner dispenser;

FIG. 8 is a bottom plan view of the liner dispenser;

FIG. 9 is a front elevational view of the liner dispenser, the rear elevational view being identical thereto;

FIG. 10 is a side elevational view of the left hand side of the liner dispenser, the right hand side view being identical thereto.

I claim:

An ornamental design for a combined waste receptacle and dispenser for disposable liners, substantially as shown and described.
